UNITED STATES PATENT OFFICE.

FRANK R. HENRY, OF ST. LOUIS, MISSOURI, ASSIGNOR TO MAJESTIC MANUFACTURING COMPANY, OF ST. LOUIS, MISSOURI.

DESIGN FOR A STOVE-FRONT.

42,393.

Specification for Design.

Patented Apr. 9, 1912.

Application filed December 1, 1911. Serial No. 663,455. Term of patent 14 years.

To all whom it may concern:

Be it known that I, FRANK R. HENRY, a citizen of the United States, residing at St. Louis, in the State of Missouri, have invented a new, original, and ornamental Design for Stove-Fronts, of which the following is a specification, reference being had to the accompanying drawing, forming part thereof.

Figure I is a front elevation of a stove

front, showing my new design. Fig. II is a side elevation of a stove front, showing my new design.

I claim:—

The ornamental design for a stove front, as shown.

FRANK R. HENRY.
